UNITED STATES PATENT OFFICE

GEORGE HOFMANN, OF LYONS, ILLINOIS

FURNACE

Application filed July 3, 1929, Serial No. 375,821. Renewed November 10, 1931.

My invention relates more particularly, though not exclusively, to oil-fired furnaces of the kind comprising a deflector in the combustion chamber of the furnace positioned for the discharge thereagainst of the combustion mixture and having its underside so shaped as to deflect the combustion mixture laterally, preferably in opposite directions and toward the side walls of the furnace, a furnace of this kind being disclosed in my pending application for United States Letters Patent Ser. No. 162,066, filed January 19, 1927. (United States Letters Patent No. 1,727,598, granted September 10, 1929).

In furnaces of this kind the combustion mixture is caused to travel along the underside of the deflector, toward the rear end of the furnace, it being one of my objects to produce such flow of the combustion mixture from the burner discharging at an angle to this surface, as for example, and more particularly, upwardly against the latter.

Referring to the accompanying drawings:

Figure 1 is a view in longitudinal sectional elevation of the lower portion of a furnace embodying my invention.

Figure 2 is a view in elevation taken at the line 2—2 on Fig. 1 and viewed in the direction of the arrows.

Figure 3 is a view in longitudinal sectional elevation of the valve-equipped portion of a pipe of the apparatus of Fig. 1 through which fluid is supplied to the furnace.

Figure 4 is a section taken at the line 4—4 on Fig. 3 and viewed in the direction of the arrows; and

Figure 5, a section taken at the line 5—5 on Fig. 1 and viewed in the direction of the arrows.

Referring to the construction shown, the combustion chamber of a furnace is represented at 5, this chamber containing a deflector 6 which may be, and preferably is, hollow, it being connected at its lower front end with a pipe 7 for connection with a water supply and at its upper rear end with an outlet pipe 8 which, where the furnace is a hot water or steam boiler, preferably communicates with the water flues thereof.

The deflector 6 which is of the same general

type as that disclosed in my above-referred-to application for patent and substantially of the specific construction shown in another application for patent filed by me concurrently herewith, Serial No. 375,822, filed July 3, 1929, is formed of a hollow body portion 9 of general semi-cylindrical form with its upper surface curved, as shown, the body 9 having a hollow fin, or keel portion, 9^a. The fin, or keel portion, 9^a inclines at its bottom surface upwardly and rearwardly finally merging at the rear end of the member 6 into the plane of the undersurface of the main portion of the body 9 as shown, the upper portion of the forward extremity of the fin, or keel portion, which is represented at 9^b and is in direct alinement with the air-inlet hereinafter referred to, being substantially vertical and of substantial knife-edge form as shown, with its side surfaces curving outwardly and rearwardly in opposite directions as represented at 9^c. Immediately to the rear of the front portion of the fin just described, the fin bulges laterally outwardly in opposite directions as represented at 9^d, its lower lateral edges from these points rearwardly being practically straight and diverging as represented at 9^e.

The shape of the deflector 6 at its underside is thus such that combustion mixture supplied to the front end of the deflector and traveling along the lower portion thereof is caused to be deflected laterally outwardly in opposite directions from the fin 9^a along substantially the full length of the deflector 6.

In the construction shown the fuel for heating the furnace is discharged upwardly at the front end of the deflector 6, the structure to this end being provided with a burner 11 shown as of a conventional oil burning type the oil for consumption therein being supplied in any suitable way through a pipe 12, and combustion-supporting fluid, as for example air, supplied through a pipe 13 for mixture with the fuel at the burner 11; the burner being located below the deflector 6 and, according to the particular construction shown, directly beneath, and in axial alinement vertically with, the forward end of the fin 9^a, whereby a portion of the upward dis-

charge from the burner 11 is split by the fin 9^a substantially one-half of such portion of the discharge passing upwardly along one side of the fin and the remainder of such portion of the discharge passing along the opposite side of the fin, the underside of the portion of the fin directly above the burner being preferably rounded as shown and provided with a centrally disposed depending knife-edge bead as represented at 9^b.

The ignited discharge from the burner 11 is caused to travel lengthwise of the deflector 6 along the underside of the latter, by directing fluid, as for example combustion-sup- 15 porting fluid, against the discharge from the burner 11 and forcing it along the underside of the deflector. To this end the furnace is equipped with a conduit 14 shown as extending at its rear open end through the front wall of the combustion chamber 5 and disposed substantially in line with the fin 9^a.

The fluid supplied through the pipe 14 is preferably such as will support combustion, this fluid being preferably air. Likewise the 25 fluid supplied through the pipe 13 is also preferably air, the pipe 13 being shown as communicating, for its source of supply, with the pipe 14 which, in the arrangement shown, would be connected, for its supply, with any 30 suitable air-forcing means. Thus in the operation of the burner air would be supplied through both of the pipes 13 and 14, the air supplied through the pipe 13 mixing with the fuel, and the air discharging 35 through the pipe 14 forcing the discharge from the burner along the underside of the deflector and aiding in the combustion of the fuel.

The pipes 13 and 14 are shown as provided 40 with means, represented at 15 and 16, whereby the flow of air therethrough may be separately controlled to adapt the apparatus for functioning in the most desirable manner depending upon the particular conditions 45 presented. Any suitable means for this purpose may be provided as for example the means 16 shown in Fig. 3 and comprising a disk-partition 17 located in the pipe 14 and having a spindle 19 on which a disk shutter 50 20 having an operating handle 21 extending through a slot 22 in the pipe 14, is pivoted.

The disk 20 contains openings 23 grouped about its center, as for example as shown, and the disk 17 contains openings 18 of substantially the same size, number and disposition relative to its axis as in the case of the disk 20. The openings in the disks are spaced apart preferably such a distance from each other that the disk shutter 20 may be 55 rotated from the position shown in Fig. 3 in which the openings 18 are fully uncovered, into a position in which these openings are fully covered or are only partially covered and to any desired degree. Thus the amount 60 of air discharging through the pipe 14 may

be accurately regulated. The same feature of regulation is also present in the controlling mechanism 15 for pipe 13.

While I have illustrated and described a particular embodiment of my invention, I do not wish to be understood as intending to limit it thereto, as the same may be variously modified and altered and the invention embodied in other forms of structure without departing from the spirit of my invention.

What I claim as new, and desire to secure by Letters Patent, is:

1. In a furnace, the combination with its combustion chamber, of a deflector therein having an under surface so shaped as to cause combustion mixture flowing along said surface to be deflected laterally, a burner located adjacent said deflector, a conduit arranged substantially in line with said deflector for directing fluid against the discharge from said burner and forcing it along said surface, and means for supplying fluid to said conduit.

2. In a furnace, the combination with its combustion chamber, of a deflector therein having an under surface so shaped as to cause combustion mixture flowing along said surface to be deflected laterally, a burner located below said deflector and discharging upwardly against the latter, a conduit arranged substantially in line with said deflector for directing fluid against the discharge from said burner and forcing it along said surface, and means for supplying fluid to said conduit.

3. In a furnace, the combination with its combustion chamber, of a deflector therein having an under surface so shaped as to cause combustion mixture flowing along said surface to be deflected laterally in opposite directions, a burner located adjacent said deflector, a conduit arranged substantially in line with said deflector for directing fluid against the discharge from said burner and forcing it along said surface, and means for supplying fluid to said conduit.

4. In a furnace, the combination with its combustion chamber, of a deflector therein having an under surface so shaped as to cause combustion mixture flowing along said surface to be deflected laterally in opposite directions, a burner located below said deflector and discharging upwardly against the latter, a conduit arranged substantially in line with said deflector for directing fluid against the discharge from said burner and forcing it along said surface, and means for supplying fluid to said conduit.

5. In a furnace, the combination with its combustion chamber, of a deflector therein having an under surface so shaped as to cause combustion mixture flowing along said surface to be deflected laterally, a burner located adjacent said deflector, means for supplying fluid to said burner, a conduit arranged substantially in line with said de-

- 5 flector for directing combustion-supporting fluid against the discharge from said burner and forcing it along said surface, a second conduit communicating with said first-named
- 5 10 6. In a furnace, the combination with its combustion chamber, of a deflector therein having an under surface so shaped as to cause combustion mixture flowing along said surface to be deflected laterally, a burner located
- 15 15 below said deflector and discharging upwardly against the latter, means for supplying fluid fuel to said burner, a conduit arranged substantially in line with said deflector for directing combustion-supporting
- 20 20 fluid against the discharge from said burner and forcing it along said surface, a second conduit communicating with said first-named conduit for supplying combustion-supporting fluid to said burner, means for forcing
- 25 25 combustion-supporting fluid through said conduits, and means for varying the proportions of fluid discharging from said conduits.
7. In a furnace, the combination with its
- 30 30 combustion chamber, of a deflector therein having an under surface so shaped as to cause combustion mixture flowing along said surface to be deflected laterally, a burner located adjacent said deflector, means for supplying
- 35 35 fluid fuel to said burner, a conduit arranged substantially in line with said deflector for directing combustion-supporting fluid against the discharge from said burner and forcing it along said surface, a second con-
- 40 40 duit communicating with said first-named conduit for supplying combustion-supporting fluid to said burner, means for forcing combustion-supporting fluid through said conduits, and means for separately control-
- 45 45 ling flow of fluid through said conduits.
8. In a furnace, the combination with its combustion chamber, of a deflector therein having an under surface so shaped as to cause combustion mixture flowing along said sur-
- 50 50 face to be deflected laterally, a burner located below said deflector and discharging upwardly against the latter, means for supplying fluid fuel to said burner, a conduit arranged substantially in line with said de-
- 55 55 flector for directing combustion-supporting fluid against the discharge from said burner and forcing it along said surface, a second conduit communicating with said first-named conduit for supplying combustion-support-
- 60 60 ing fluid to said burner, means for forcing combustion-supporting fluid through said conduits, and means for separately control-
- 65 ling flow of fluid through said conduits.

GEORGE HOFMANN.
